(57) **CLAIM**

The ornamental design for a cigarette lighter, as shown and described.

DESCRIPTION

1. Cigarette lighter

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

The design application includes design 1 designated as the basic design; the gist of the design 1 is shape and pattern of “cigarette lighter”; product shown in design 1 is a cigarette lighter.

The broken lines in 1.5 depict portions of the cigarette lighter that form no part of the claimed design.
